UNITED STATES PATENT OFFICE

2,672,540

BANDED MULTIPLE ELEMENT FUSE

Clyde G. Dewey, Philadelphia, Pa., assignor to
General Electric Company, a corporation of
New York

Application March 20, 1953, Serial No. 343,718

3 Claims. (Cl. 200—121)

1

The invention relates to fuses and more particularly to power fuse units of the current limiting type having a plurality of fusible elements operating in parallel current interrupting relation.

Such power fuse units are extensively used in lieu of the relatively more expensive and larger size circuit breakers for protecting relatively high voltage power circuits upon the occurrence of faults, particularly short circuits. In such short circuit protective service, the multi-element current limiting type of fuse has the outstanding advantage over circuit breakers of initially limiting the excess current to a value which is only a fraction of that which the power circuit is otherwise capable of supplying.

To obtain such current limiting action, the multiple fuse elements ordinarily are in the form of relatively long fine wires of a readily vaporizable metal such as silver or zinc and embedded in intimate heat exchange relation throughout their active length in an inert, granular refractory arc extinguishing material of high dielectric strength, such as sand, or relatively finely divided quartz. The embedded elements are enclosed in an insulating fuse casing or housing having terminals mounted thereon for connecting the fusible elements in parallel current interrupting relation.

Upon subjection of such a fuse unit to fault currents of a high voltage circuit such as produced by a short circuit, the spaced apart fusible elements, if all conditions are equal, will each attain fusing temperature and dissipate or vaporize throughout a fusible section of considerable length, whereupon parallel arcing will occur and the metal vapors rapidly expand. The force of such expansion will throw the metal vapors out of the arc paths and into the spaces between the granules of the inert filler material separating the fusible elements. As a result, these vapors rapidly condense upon the surface of the relatively cool granules and no longer are available for current conduction so that each arc is confined to the elongated and restricted path previously occupied by the corresponding fusible element. The intimate heat exchange relation between the spaced apart parallel elongated hot arc columns and the relatively cool granules will, if all conditions are equal, cause an exceedingly rapid transfer of heat from each arc column to the adjacent granules so that the arc energy is quickly dissipated by this heat transfer with practically negligible net pressure on the fusing housing.

2

As a result of the fusing of the parallel elements in the manner outlined above there will be in effect suddenly inserted into the path of the current at the instant of vaporization of the parallel fusible elements a high resistance formed by the elongated parallel arc columns which will initially limit the current to a magnitude which is only a fraction of the current which the short circuit is otherwise capable of producing. The inserted resistance will cause rapid current decay and the quick cooling of the arcs will produce a subsequent interruption of the current flow in short circuits within the interrupting capacity of the fuse unit. But whenever such interrupting capacity is exceeded or whenever all conditions are not equal the multiple element fuse unit may fail to extinguish some one or more of the parallel arcs resulting from the fusing of the parallel elements and therefore fail to successfully interrupt the short circuit.

As the use of such current limiting power fuse units becomes extended to even higher voltage power circuits the problem of correspondingly increasing the voltage interrupting ability of a multiple element fuse unit with a construction of economic size and manufacturing cost becomes more acute.

Thus, the principal object of the present invention is to provide an improved means for increasing the voltage interrupting ability of a multiple element current limiting fuse unit without increasing its size or length or materially increasing its cost.

In accordance with the present invention, this is accomplished by providing conducting members or bands for interconnecting the elongated fusible elements in parallel current equalizing relation at spaced intervals along their length. Since these elements are connected in parallel current interrupting relation by the fuse terminals at the ends of the elements, the effect of the additional intermediate conducting members or bands is to cause the current to divide more evenly both before and during circuit interrupting conditions in the sections of the fusible elements between the bands than it may in the end sections. Such current equalization produces more equal distribution of the interrupting duty between the elements. This has been established by test as the successful voltage interrupting ability of a multiple element current limiting fuse has been substantially improved solely by the provision of the equalizing conducting members or bands interconnecting the fusible elements at spaced intervals along their length.

A further effect of the bands is to cause each current limiting fuse element to produce more voltage drop at any value of current since the voltage gradient is always higher at the ends of an arc than at the intermediate portions of the arc. Thus, the bands of the present invention in effect provide additional arcing terminals intermediate the end terminals of the multiple elements of the fuse. In this way the total arc drop resistance of the fuse unit is materially increased.

But upon operation of a current limiting fuse in a highly inductive circuit, the sudden insertion of a relatively high arc drop resistance and rapid decay of the current may result in a voltage surge which under some conditions may attain a magnitude sufficiently high to damage other apparatus in the circuit. It is therefore desirable to limit any voltage surge to a safe magnitude by forming the fusible elements so as to secure a relatively gradual or stepped insertion of the arc resistance into the circuit. This result has usually been obtained by providing each fuse element with sections of different fusing current capacity. Thus the fuse elements may be provided with sections of different cross sectional area or with sections of different resistance characteristics such that sequential or step-by-step fusing and dissipation of the fusible sections of each element is secured. In either case, when the different sections of the elements are formed to fuse in sequence, the interconnecting conducting members or bands of the present invention preferably are applied to interconnect the elements at the junctions of the sections and preferably with the section that will first fuse intermediate the bands so as more effectively to produce the joint fusing of the different sections of all elements in the desired sequence.

Further objects and advantages of the invention will become apparent from the following description of the accompanying drawings and the features of novelty which characterize the invention will be pointed out with particularity in the appended claims.

In the drawing,

Fig. 1 is a side view partly in section of a typical multiple element current limiting power fuse unit embodying the improvements of the present invention;

Fig. 2 is a cross section view of the fuse unit shown in Fig. 1 on the sectional line 2-2 with the inert arc resistance material omitted;

Fig. 3 is a chart indicating the relative increase in voltage interrupting capacity of multiple element fuse units attained by means of the improvements of the present invention.

A typical multiple element current limiting fuse unit construction is illustrated in Fig. 1 as comprising an enclosing tubular casing 10 formed of suitable insulating material such as fiber or glass and having the fuse terminals 11 and 12 mounted on the opposite ends thereof by means of suitable sealing material 13. As shown in Figs. 1 and 2, three symmetrically spaced fusible element insulating and supporting cores 15, 16, and 17, of ceramic material are mounted inside the casing 10 to extend substantially the full length of the casing. As illustrated, each core has four projecting ribs 18 so as to form an elongated square frame or reel upon which a plurality of fusible elements 19 are wound in uniformly spaced apart relation to be separately embedded in the granular refractory material 14, as shown three fusible elements 19

are wound on each core. In this way, the multiple fusible elements of the required length for relatively high voltage circuits can be mounted in a fuse unit of economic and practical over-all length. For example, where the voltage of the circuit may require each fuse element to be about 4 or 5 feet in length, the over-all length of each core as well as the fuse unit itself may be maintained less than 2 feet.

The number of cores and the number of fusible elements wound on each core will of course vary dependent upon the maximum continuous current carrying rating of the fuse. The core construction and the winding of the fusible elements in spaced apart relation thereon preferably is such that the elements are uniformly distributed throughout the available space inside of the fuse casing 10. Thus, when the casing is filled with the finely divided sand or other inert arc resistance material 14, each fusible element will throughout its active length be embedded in intimate heat conducting relation with this material and sufficiently isolated from the adjacent elements to obtain individual current limiting and arc extinguishing action of the parallel elements.

As shown, the three cores 15, 16, and 17, are mounted in symmetrically spaced apart relation inside casing 10 by means of a spacer plate 20 at each end and secured in position by the holding screws 21. The multiple fusible elements 19 on each core are interconnected in parallel current interrupting relation at the ends thereof by means of a common terminal 22 which extends through suitable openings in the spacer plate 20 and is joined as by welding to one of the fuse terminals 11 or 12. In this way, all of the elements 19 on all of the cores are connected between terminals 11 and 12 in parallel current interrupting relation.

In accordance with the present invention, the current equalizing conducting members or bands 24 and 25 are provided for interconnecting all of the fusible elements 19 at spaced intervals intermediate their ends to increase the voltage interrupting ability of the fuse unit. As shown, the three fusible elements 19 wound on each core are interconnected in current equalizing relation by the bands 24 and 25 at equally spaced intervals intermediate their ends and the corresponding bands on each core are then interconnected by suitable jumpers 27 so as to electrically interconnect all of the elements on all of the cores. If desired, the separate bands 24 and 25 on each core may be formed simply by winding

and welding a few turns of bare silver or zinc wire to interconnect all the fusible elements thereon and twisting the ends of the wire together and leaving these ends sufficiently long for convenient joining as by welding with the ends of the current equalizing bands on the adjacent cores.

When the fusible elements are provided with sections of different fusing current capacity and arranged so that the middle section will fuse before either of the end sections, then the bands 24 and 25 are located adjacent to or overlying the junctions between the different sections of the fusible elements so as to thereby interconnect each of the corresponding sections of each of the elements in current equalizing relation.

It has been found by test wherein the test circuit voltage is increased that a multiple element current limiting fuse unit provided with current equalizing bands constructed and arranged as de-

scribed above will have an increased voltage interrupting ability over that provided by the same fuse unit without the bands. Fig. 3 has been plotted from the results of these tests to indicate the substantial increase in successful interrupting ability that was obtained solely by applying the current equalizing bands in accordance with the present invention. As indicated in Fig. 3, the length of a multiple element fuse unit normally required for successful interruption will increase as indicated by the dotted line A as the voltage of the circuit is increased. Thus the over-all length of the fuse unit of the same internal construction becomes a fairly accurate indication of the successful voltage interrupting ability thereof. The solid line B shows that when a pair of current equalizing bands are applied to the multiple element fuse unit, a substantial increase in successful voltage interrupting ability thereof is obtained without any increase whatever in over-all length of the unit.

While there may be various technical theories as to why the provision of the current equalizing bands intermediate the ends of the multiple element fuse in accordance with the present invention provide the improved results indicated by Fig. 3, this can be explained most satisfactorily on the basis of the equalization of the current in all sections of all of the elements. Such current equalization more effectively insures that each section of each element will participate in and share the joint circuit interrupting duty. In this way the bands effectively prevent a disproportionate share of the circuit interrupting duty becoming imposed upon some one element so that the arc thereof persists and the fuse unit fails to interrupt the short circuit.

What I claim as new and desire to secure by Letters Patent of the United States is:

1. A multiple element current limiting fuse unit having in combination, a casing formed of insulat-

ing material having arc extinguishing material therein and having a pair of current conducting terminals mounted on the casing in spaced apart relation, a plurality of fusible elements in intimate heat exchange relation with the arc extinguishing material and connected in parallel current interrupting relation between the terminals, and means including a conducting member interconnecting the elements intermediate the ends thereof for equalizing the distribution of the current between the elements to increase the voltage interrupting ability of the fuse unit.

2. A multiple element current limiting fuse unit having in combination, a casing formed of insulating material having arc extinguishing material therein and having a pair of current conducting terminals mounted on the casing in spaced apart relation, a plurality of fusible elements in intimate heat exchange relation with the arc extinguishing material and connected in parallel current interrupting relation between the terminals, and means including at least a pair of conducting members interconnecting the elements at substantially equally spaced intervals intermediate the ends thereof for equalizing the distribution of the current between the elements to increase the voltage interrupting ability of the fuse unit.

3. A multiple element fuse unit having a plurality of fusible elements connected in parallel current interrupting relation and each element having sections of different fusing current capacity to produce sequential fusing thereof, and means including a conducting member interconnecting the junctions between the sections of the elements for equalizing the distribution of the current to increase the voltage interrupting ability of the fuse unit.
